DESIGN FOR A BOTTLE LIFTER

Homer C. Miller, Findlay, Ohio

Application March 20, 1944, Serial No. 112,971

Term of patent 7 years

(Cl. D44—29)

To all whom it may concern:

Be it known that I, Homer C. Miller, a citizen of the United States, residing at Findlay, in the county of Hancock and State of Ohio, have invented a new, original, and ornamental Design for a Bottle Lifter, of which the following is a specification, reference being had to the accompanying drawing, forming part thereof.

In Figures 1, 2 and 3, the handle is shown broken and shortened for convenience of illustration.

I claim:

The ornamental design for a bottle lifter, as shown and described.

HOMER C. MILLER.
